UNITED STATES PATENT OFFICE.

ARTHUR WITHALL, OF CHICAGO, ILLINOIS, ASSIGNOR TO AMERICAN STEEL FOUNDRIES, OF CHICAGO, ILLINOIS, A CORPORATION OF NEW JERSEY.

CAST-STEEL BOTTOM-DROP DOOR.

Application filed September 27, 1928. Serial No. 308,634.

This invention relates to cast metal doors, and is illustrated herein as embodied in a door of a type suitable for use in connection with railway dump cars.

Heretofore there has been developed and patented a multitude of doors adapted for use in connection with dump cars, and among these prior developments there are to be found several patents which relate to doors made in a single piece casting. Such a door is desirable inasmuch as it is comparatively inexpensive to manufacture, and contains no separate fastening elements that, owing to the severe use to which the doors are put, are likely to break. These desirable considerations notwithstanding, it has been found that the cast doors of the prior art patents are open to one of several objections: the doors are cast in such a manner that they are highly subject to breakage, or if cast with the required degree of strength and durability, they are so heavy and of such a thickness as to render them unpractical in use and operation.

In view of the foregoing considerations, the present invention has for an important object thereof the provision of a single piece cast door which, although comparatively thin in cross section, is of sufficient strength and durability to withstand the shocks and jars to which doors of this type are generally subjected.

The door disclosed in the present application, as well as those disclosed in many of the prior art patents, comprises a substantially rectangular load engaging surface which is surrounded by a downwardly depending flange and is provided with suitable reinforcements. Heretofore in casting hinge lugs integrally with the door, they have been formed on the outside surface of the flange and in order to reenforce the structure, webs have been formed which terminate on the inside surface of the flange immediately opposite to the hinge lugs. Reenforcements of this nature however, do not tend materially to strengthen the hinges inasmuch as the flange is interposed between the reenforcing members

and the hinge lugs, and in use of such doors the hinge lugs are apt to shear or break from the outside surface of the flange. The reason for this can well be appreciated when one considers that a prodigious weight of material dumped suddenly upon the load engaging surface of the door must be supported solely by the hinge lugs which join the door to the railway car along one side of the door.

In view of this tendency to shear, the present invention has for an important object thereof, the provision of a single piece cast door for dump cars comprising a flat load engaging surface, a downwardly depending flange, and hinge lugs located directly beneath the flange and connected thereto. With the hinge lugs formed in this manner, there is no shearing action whatsoever that takes place between the door and the lugs when a load is suddenly deposited in a car. The only action which takes place in loading a car is that the metal in the flange and in the hinge is compressed and this in no way tends to weaken or break the door.

In order to increase still further the strength and durability of the door and more particularly to prevent the hinge lugs from being severed from the flange with which they are connected, the present invention contemplates extending reenforcing members across the lower side of the load engaging surface and terminating the members by merging them into the hinge lugs. Thus, the hinge lugs are, in fact, carried by the reenforcing members and this kind of structure is to be contrasted with the structures of the prior art in which reenforcing members and the hinge lugs are disposed on opposite sides of the downwardly depending flange.

A further feature of the invention consists in the manner in which the load engaging surface itself is reenforced to prevent cracking or undue warpage. It has been found that a considerable strain is imparted to the door while the material is being spilled from the car and this strain

takes place in the direction the material flows in spilling. With this in view, the invention contemplates providing the door with reenforcements extending in the direction the material flows in spilling and in making these reenforcements sufficiently strong and heavy to withstand readily the strain which is imparted to the door during a spilling operation. Inasmuch as the strain imparted to the door in a direction extending transverse to that in which the material flows in spilling is comparatively small, the invention contemplates providing transverse reenforcing members that are light whereby a balance between the reenforcing members and the bending strains has been effected.

Another feature of the invention consists in providing the comparatively heavy reenforcing strips with means for cooperating with apparatus used in opening and closing the door. In the illustrated embodiment of the invention, this feature is carried out by providing the reenforcing member with a flat runway over which rollers run in opening and closing the door.

Other objects and features of the invention will become apparent from a reading of the following specification in the light of the accompanying drawings in which—

Figure 1 is a view in perspective of the lower surface of a dump car door;

Figure 2 is a view in side elevation of the door shown in Figure 1;

Figure 3 is a diagrammatic view of a section of the door;

Figure 4 is a view in end elevation in section of the door shown in Figure 1; and,

Figure 5 is a fragmentary view showing a modification of the door shown in Figure 1.

As shown in the drawings, the door comprises generally an approximately rectangular load engaging surface 10 and a downwardly extending peripheral flange 12 which completely surrounds the outside edge of the door. As illustrated, the load engaging surface 10 is flat, but it is to be understood that if desired the surface may be provided with corrugations or with other configurations of any desired size or shape. Similarly, the downwardly depending flange 12 has been flared outwardly along the sides of the door as shown in Figure 4, but here again, the outwardly flared flanges may be employed at the ends of the door or vertical flanges may be employed along the sides without departing in the least from the scope of the invention.

In order properly to reinforce the structure, the opposite ends of the door are reinforced in some suitable manner. In the illustrated embodiment of the invention, one end 16 of the door has been reinforced satisfactorily by resorting to the common

expedient of providing a reentrant flange 18 and the opposite end 14 has been similarly strengthened by employing an ordinary thickened flange 14^a. From so much of the description as has been given, it will be understood that the load engaging surface 10 is surrounded by a peripheral flange which is flared outwardly along the sides of the surface and is reenforced in a suitable fashion at the opposite ends of the surface.

To the end of maintaining the door in position within the bottom of a railway dump car, there are provided a plurality of hinge lugs 24, 24 arranged along one end of the door which, for the sake of convenience, may be termed the "hinge end" or "hinge side". Heretofore, it has been customary to form the hinge lugs on the outside of the flange and in such a position it has been found that the lugs break and shear off thereby rendering the door inoperative. To the end of preventing this, the present invention contemplates forming the hinge lugs in the manner illustrated in Figures 1 and 2 directly beneath the downwardly depending flange whereby shearing action is completely eliminated. It will be observed that the hinge lugs are connected to the end 16 of the door by means of integrally formed connecting portions, but the lugs are, properly speaking, carried by the extremities of reenforcing members 20, 20. These latter named members extend parallel to one another in the lengthwise direction of the door and are higher than the depending flange as shown in Figure 2. As also shown in the same figure, the reenforcing members at their righthand extremities are higher than the flange and are formed in such a manner as to merge into and carry as integral parts the hinge lugs 24, 24.

Speaking more specifically, the reenforcing members comprise runways 20 across the surface of which are adapted to travel rollers utilized in opening and closing the door, and flange or web portions 22, 22 located beneath the runways 20, 20. The reenforcing members which are composed of the runways 20, 20 and webs 22, 22 extend in a direction that the load moves in dumping and since it has been found that during the dumping operation a considerable strain is imparted to the door in the direction the material is moving, these reenforcing members are made considerably heavy in order properly to withstand such strain. On the other hand, the strain imparted to the door in a direction transverse to that in which the load moves is comparatively small and in order to provide a balanced proportion between the strains and the reinforcements, a plurality of comparatively light or small reenforcing webs 30, 30 extend transversely of the heavy reenforcing members and serve properly to brace the door transversely of

the direction in which the load moves in spilling or dumping.

As shown in Figure 5, the downwardly depending flange is indicated by the reference numeral 32 and is reenforced by means of fillet members 34. It is to be appreciated, however, that the flanges may be strengthened by the employment of any common expedient, as, for example, reentrant flanges 10 may be provided on the side 14 of the door in place of the thickened portion 14a.

It has been heretofore pointed out that in casting a door that is reenforced and constructed in the aforescribed manner a 15 panel comparatively thin in cross section may serve for the load engaging surface and this is an extremely important aspect of the invention since the features of lightness and inexpensiveness are important factors in the manufacture of these doors.

It has been stated that the door is a cast door and it is to be understood that the materials employed in casting the door may be any suitable metals or combinations of 25 metals, as, for example, aluminum, metal alloys, etc. It is likewise to be understood that the invention contemplates changes and modifications in design and construction which will from time to time occur to those 30 skilled in the art and it is to be recognized that the introduction of such changes into other doors will not effect a departure from the scope of the present invention as pointed out in the appended claims.

Having thus described my invention what I claim as new and desire to secure by United States Letters Patent is:

1. A single piece cast door for dump cars, comprising, a load engaging surface, a 40 downwardly extending flange arranged peripherally of the load engaging surface, a plurality of reenforcing members extending parallel to one another across the lower side of the load engaging surface, and hinge 45 lugs integrally formed directly upon the extremities of the reenforcing members.

2. A single piece cast door for dump cars, comprising, a load engaging surface, a 50 downwardly extending flange arranged peripherally of the load engaging surface, a plurality of reenforcing members extending parallel to one another across the lower side of the load engaging surface, and hinge lugs integrally formed directly upon the 55 extremities of the reenforcing members, said reenforcing members being shaped to co-operate with apparatus for use in opening and closing the door.

3. A single piece cast door for dump cars, 60 comprising, a load engaging surface, a downwardly extending flange arranged peripherally of the load engaging surface, a plurality of reenforcing members extending parallel to one another across the lower side 65 of the load engaging surface, and hinge lugs

integrally formed directly upon the extremities of the reenforcing members, said reenforcing members being provided with flat runways adapted to be frictionally engaged by apparatus for opening and closing the 70 door.

4. A single piece cast door for dump cars, comprising, a load engaging surface, a 75 downwardly extending flange arranged peripherally of the load engaging surface, the lower edge of the flange being widened along one side of the door, a plurality of reenforcing members extending across the lower side of the load engaging surface, and a plurality of hinge lugs carried directly upon the 80 extremities of the reenforcing members, said hinge lugs being integrally connected to the widened lower edge of the flange.

5. A single piece cast door for dump cars, comprising, a load engaging surface, a 85 downwardly extending flange arranged peripherally of the load engaging surface, and a plurality of integrally formed hinge lugs located directly beneath the said flange.

6. A single piece cast door for dump cars, comprising, a load engaging surface, a 90 downwardly extending flange arranged peripherally of the load engaging surface, and a plurality of integrally formed hinge lugs located directly beneath the said flange, and 95 carried by an equal plurality of reenforcing members.

7. A single piece cast door for dump cars, comprising, a load engaging surface, a 100 downwardly extending flange arranged peripherally of the load engaging surface, and a plurality of integrally formed hinge lugs located directly beneath the said flange, said hinge lugs being carried by an equal plurality of reenforcing members and being 105 connected to the flange by means of integrally cast connecting portions.

8. A single piece cast door for dump cars, comprising, a load engaging surface, a 110 plurality of comparatively heavy reenforcing members extending beneath the under side of the load engaging surface in the direction in which the load moves in dumping, and a plurality of comparatively light reenforcing flanges extending transversely of 115 the heavy reenforcing members.

9. A single piece cast door for dump cars, comprising, a load engaging surface, a 120 plurality of comparatively heavy reenforcing members extending beneath the under side of the load engaging surface in the direction in which the load moves in dumping, and a plurality of comparatively light reenforcing flanges extending transversely of the heavy reenforcing members, said latter 125 named members being provided at their terminals with integrally cast hinge lugs.

10. A single piece cast door for dump cars, comprising a load engaging surface, a plurality of comparatively heavy reenforcing 130

members extending beneath the under side with a portion adapted to cooperate with of the load engaging surface in the direction apparatus for opening and closing the door, in which the load moves in dumping, and a and with integrally cast hinge lugs. 10
5 plurality of comparatively light reenforcing Signed at Chicago, Illinois, this 24th day flanges extending transversely of the heavy of September, 1928.
reenforcing members and terminating short thereof, said heavy members being formed

ARTHUR WITHALL.
